(57) **CLAIM**

The ornamental design for a tumbler with lid, as shown and described.

DESCRIPTION

1. Tumbler with lid

Fig. 1.1 is a perspective view showing my new design; Fig. 1.2 is a front view thereof, the back view being the same as the front view;

Fig. 1.3 is a top plan view thereof;

Fig. 1.4 is a bottom plan view thereof;

Fig. 1.5 is a right side view thereof, the left side view being the same as the right side view; and

Fig. 1.6 is a perspective view with the lid removed.

The portions of the tumbler with lid shown in broken lines form no part of the claimed design.

1 Claim, 6 Drawing Sheets
